UNITED STATES PATENT OFFICE

WILLIAM EARL GUNN, OF GRAND RAPIDS, MICHIGAN, ASSIGNOR TO GUNN FURNITURE COMPANY, OF GRAND RAPIDS, MICHIGAN, A CORPORATION OF MICHIGAN

DESIGN FOR A DESK

Application filed September 17, 1930. Serial No. 37,002. Term of patent 3½ years.

To all whom it may concern:

Be it known that I, WILLIAM EARL GUNN, a citizen of the United States, residing at the city of Grand Rapids, in the county of Kent and State of Michigan, have invented a new, original, and ornamental Design for Desk, of which the following is a specification, reference being had to the accompanying drawings, forming a part thereof.

Fig. 1 is a perspective view of a front and end of a desk showing my new design.

Fig. 2 is a perspective view of the rear and end of the same.

I claim:

The ornamental design for a desk, as shown.

WILLIAM EARL GUNN.
